UNITED STATES PATENT OFFICE

146,406

DESIGN FOR A CLOCKCASE

Vasile Faor, Fort Wayne, Ind.

Application August 29, 1946, Serial No. 132,948

Term of patent 14 years

(Cl. D42—7)

To all whom it may concern:

Be it known that I, Vasile Faor, a citizen of the United States, residing at Fort Wayne, in the county of Allen and State of Indiana, have invented a new, original, and ornamental Design for Clockcases, of which the following is a specification, reference being had to the accompanying drawing, forming part thereof.

The drawing is an illustration of a clockcase in which the design is incorporated.

I claim:

The ornamental design for a clockcase, as shown.

VASILE FAOR.
